Primary Examiner — Sheryl Lane*Assistant Examiner* — Aula Soroush(74) *Attorney, Agent, or Firm* — Benesch Friedlander
Coplan & Aronoff LLP(57) **CLAIM**

The ornamental design for a poultry brooder, as shown and described.

DESCRIPTION

FIG. 1 is a perspective view of a poultry brooder;
 FIG. 2 is a front view of the poultry brooder;
 FIG. 3 is a rear view the poultry brooder;
 FIG. 4 is a left side view the poultry brooder;
 FIG. 5 is a right side view the poultry brooder;
 FIG. 6 is a top plan view the poultry brooder;
 FIG. 7 is a bottom plan view the poultry brooder; and,
 FIG. 8 is a perspective view of the poultry brooder.
 The broken lines in FIGS. 1-8 show portions of the poultry brooder which form no part of the claimed design, and other broken lines shown in FIG. 8, that are not otherwise shown in FIGS. 1-7, illustrate environmental context.
